UNITED STATES PATENT OFFICE.

MAURICE EUGENE RICKER, OF KALONA, IOWA.

LEAKLESS CREAM-CAN LID.

Application filed February 16, 1926. Serial No. 88,605.

This invention aims to provide a simple but sanitary means for holding a closure tightly in a cream can or other container.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in vertical section, a portion of a can equipped with the device forming the subject matter of this application;

Figure 2 is a top plan wherein parts are broken away;

Figure 3 is a transverse section;

Figure 4 is a longitudinal section taken about at right angles to the showing of Figure 1;

Figure 5 is a cross section of the retainer.

The numeral 1 designates a cream can or other container including a neck 2 having a flared part 3 within which is secured a conical keeper 4, in the form of a ring, the keeper being provided with ribs 6. Sometimes the body of the can has openings 5 adapted to receive a seal or the like, not shown, and when these openings 5 exist in the can, they are closed up when the keeper or ring 4 is mounted in place.

A retainer 9, in the form of a ring, is secured in the neck 2. In its inner edge, the retainer 9 has passages 10 disposed parallel to the axis of the can 1. On its under-surface, the retainer 9 is supplied with circumferentially slanting cam surfaces 11 which lead from the passages or notches 10.

A cup-shaped closure 7 fits in the neck 2 and is provided at its upper end with a guard 8 which extends outwardly and downwardly about the part 3 of the neck 2 to aid in keeping out dirt. A tubular handle 12 is mounted at its ends on the side wall of the closure 7.

A latch 14 is mounted for reciprocation in the handle 12. The latch 14 includes a body 15, a reduced stem 16 projecting from

the body, and a foot 18 held detachably but securely on the stem 16 by an attaching element 17. The outer end of the foot 18 of the latch 14 is reduced at 19 to fit between the ribs 6 and the keeper 4. A washer 20 is disposed about the stem 16 and engages the inner end of the foot 18. A washer 21 likewise extends about the stem 16 and is located in the handle 12. Securing elements 22, mounted in the handle 12, hold the washer 21 against inward movement. The washer 21 and the securing elements 22 form an abutment for the inner end of a compression spring 23, disposed about the stem 16

of the latch 14, the outer edge of the compression spring 23 engaging the washer 20, to advance the latch 14, so that the reduced part 19 of the latch 14 will engage with the ribs 6 on the keeper ring 4. A tubular operating member 24 is mounted to slide and to rotate on the handle 12. A securing device 25, such as a screw, connects the operating member 24 with the foot 18 of the latch 14.

The securing device 25 moves in a laterally extended slot or seat 26 that is formed in the handle 12, within the slide 24, the slot being hook-shaped, as shown in Figure 2.

The closure 7 includes a base 27, attached to the bottom of the closure and located within the retainer ring 9. In the lower surface of the disk-like base 27, there is a transverse passage 28 which is intersected by a bore 29 located at right angles to the passage. A holder 30, in the form of a bar, is located in the passage 28, and has reduced ends 31, adapted to cooperate with the cam surfaces 11 of the retainer 9, the holder 30 being mounted intermediate its ends to tilt a little on a pivot element 32, in the form of a rod, the pivot element being located in the bore 29, and being held therein by screws 33 threaded into the ends of the bore.

By means of the tubular operating member or slide 24, the latch 14 may be retracted, the spring 23 being compressed. If the operating member or slide 24 is rotated, the securing device 25 will be carried laterally in the seat or slot 26, and, thus, the latch 14 will be held retracted. The closure 17 is inserted into the neck 2 of the can 1, the body portion of the closure resting on the retainer or ring 9, and the reduced ends 31 of the bar 30 pass downwardly through the passages or notches 10 in the retainer ring 9.

Then, the closure 7 is rotated by means of the handle 12. The ends 31 of the holder 30

move along the cam surfaces 11 of the retainer ring 9, and the lower end of the body of the closure 7 is bound firmly upon the retainer 9, the part 9 serving as a seat for the closure. Then, the slide or operating member 24 may be rotated so as to permit the slide and the latch 14 to move to the left, in Figure 1, under the impulse of the spring 23, the spring 23 causing the reduced end 19 of the latch to engage between two of the ribs 6 on the keeper ring 4, the closure 7 thus being prevented from rotating, it being obvious that, if the closure 7 is reversely rotated, the ends 31 of the holder bar 30 will loose their grip on the cams 11. Owing to the fact that the holder bar 30 is pivotally mounted intermediate its ends as at 32, both of the ends 31 of the holder bar will cooperate properly with the cam surfaces 11 of the retainer ring 9, and it is necessary to form neither the cams 11 nor the ends 31 of the holder 30 with micrometric exactness, in order to secure favorable results.

25 25. What is claimed is:—

1. In a device of the class described, a container having an internal circumferential cam and provided with an internal cir-

cumferential rack, a closure rotatable in the container and provided with a handle, 30 a holder mounted on the closure and cooperating with the cam to advance the closure into the container when the closure is rotated, a spring-pressed latch slideable in the handle and normally in position to 35 automatically engage with the rack, thereby to hold the closure against rotation whilst the holder engages the cam to advance the closure as aforesaid, and means under the control of an operator for retracting the 40 latch.

2. In a device of the class described, a container having oppositely disposed circumferential cams, a closure rotatable in the container, a holder cooperating at its ends 45 with the respective cams to seat the closure when direct rotation is imparted to the closure, means for pivotally mounting the holder at a point intermediate its ends for tilting movement on the closure, and means 50 for holding the closure releasably against reverse rotation.

In testimony that I claim the foregoing as my own, I have hereto affixed my signature.

Mr. MAURICE EUGENE RICKER.
